ELECTRIC SWIVEL PLUG

Harold C. Lent, Hoopeston, Ill.

Application August 5, 1932, Serial No. 627,648

1 Claim. (Cl. 173—343)

The object of the invention is to provide an electric plug particularly adapted for use with electric sad irons, curling irons and other electrical appliances for hand use in which the conductor cord is ordinarily subjected to twisting, so that free turning movement will be provided to prevent such twist; to provide an electric plug of the character indicated which is readily separable to permit the removal of the cap portion by simple withdrawal from the base portion; and generally to provide a swivel electric plug which is of simple form and therefore susceptible of cheap manufacture.

With this object in view, the invention consists in a construction and combination of parts of which a preferred embodiment is illustrated in the accompanying drawing but to which embodiment the invention is not to be restricted. Continued use in practice may dictate certain changes or alterations and the right is claimed to make any which fall within the scope of the annexed claim.

In the drawing:

Figure 1 is a side elevational view of a plug constructed in accordance with the invention.

Figure 2 is a top plan view of the base portion.

Figure 3 is a bottom plan view of the cap portion.

Figure 4 is a central vertical sectional view, enlarged.

Consisting of the base and cap portions 10 and 11, the former, which is made of any suitable insulating material, is peripherally bound at the lower end with a circumferentially corrugated sleeve member 12, the corrugations being spirally arranged, so that a continuous thread is provided to permit the base portion being screwed into any conventional receptacle. Since the sleeve portion 12 constitutes one of the contacts of the plug, a contact strip 14 embedded in the plug is engaged with the sleeve portion 12 by contact with the inturned flange portion 15 of the latter, this inturned flange portion resting in a recessed part of the lower face of the base portion of the plug, so that the sleeve may be retained on the plug through the instrumentality of the insulating washer 16 which abuts the under face of the base portion and overlaps the inturned flange 15. The retaining insulating washer 16 is secured in place by means of a screw 17, this screw constituting the center contact of the plug and passing through a washer 18, preferably of metal, but of less diameter than the washer 16. The screw has the threaded end 19 entering a center bore of the base portion 10 of the plug where it thread-

ingly engages the web of a forked clip 20, the arms of which have a spring tendency towards each other and which at intermediate points in their length are bent inwardly as indicated at 21 to provide elements for engagement with the center contact member of the cap portion 11.

In the upper face of the base portion 10, there is formed a channel in which is seated a channel-shaped conductor strip 22 and this channel-shaped conductor strip is electrically connected with the sleeve 12 by reason of the strip 14 which is engaged with the under face of the channel-shaped conductor, as shown at 23.

The contacts in the cap portion 11 consist of members to engage the forked clip 20 and the channel-shaped conductor 22. The one comprises a plate 24 provided with a conventional binding post 25 and with a stud 26, the binding post 25 being for connection with one of the conductors 27 and the stud 26 being for engagement with the channel-shaped conductor 22. The other contact of the cap consists of a plate 28, provided with a binding post 29 for connection to the other conductor 30. The plate 28 is bent as indicated at 31 to provide a pendent stem which terminates in a knob 32 directly above which is formed a reduced cylindrical neck portion 33. In attaching the cap 11 to the base portion, the knob enters the central recess in the latter between the arms of the spring clip 20 and spreads the arms when it passes between the bends 21. The stem 31 is of sufficient length to permit the knob passing the bends 21 to bring them adjacent the neck portion 33, so that they bear on the rear end of the knob and thus have a tendency to pull the cap towards the base portion and thus bring the lug or post 26 into firm contact with the bottom or web portion of the channel conductor member 22.

To maintain axial alignment of the base and cap portion, the latter is interiorly enlarged at the lower end and the former exteriorly reduced at the upper end, so that an overlapping flange 34 is provided on the cap which surrounds the peripherally reduced portion of the base.

It will be noted of course that the construction provides for angular or turning movement of the cap portion on the base with electric conductivity always maintained since the method of engagement of the arms of the spring clip 20 insures an axial pulling movement on the cap to maintain the lug in contact with the conductor channel 22. The construction also provides for the ready separation of the cap from the base portion by an axial pull imparted to the former.

The invention having been described, what is claimed as new and useful is:

- An electric swivel plug comprising base and cap portions of which the former is provided with a recess and with a forked spring clip disposed in the same, the base portion having a center contact electrically connected to said clip for engagement with the corresponding contact of a receptacle, the cap having a center contact engageable between the arms of the spring clip of the base and the latter having a channel formed in its upper end and an annular contact in said channel and arranged concentrically of the recess in said base, said annular contact being electrically connected to a peripheral contact and being in the form of a channel with its flat face lying in a plane transverse of the base but per-

pendicular to the axis thereof, the cap having an off-center contact arranged with its axis parallel to the axis of the base and bearing on the face of said annular contact, the arms of the forked spring clip being provided with inwardly directed bends at intermediate points in their lengths and the center contact of the cap comprising a knob of greater diameter than the space between said bends and having a contracted neck portion to provide a clearance space for said bends to permit them to engage directly behind the body portion of the knob and create an axial pull on the cap to maintain the contact of the latter in constant yielding engagement with the annular contact.

HAROLD C. LENT.
